UNITED STATES PATENT OFFICE.

JOHN G. REA, OF UNION CITY, NEW JERSEY.

OIL PURIFIER AND GAS SEPARATOR FOR INTERNAL-COMBUSTION ENGINES.

Application filed May 17, 1926. Serial No. 109,770.

The present invention is concerned with an attachment for internal combustion engines which will serve to subject the crank case oil to a continuous process of filtration and purification, which will separate gasoline from the crank case oil by a continuous process of recirculation and distillation, and which will in a large measure prevent the gasoline which passes the piston rings from mixing with the oil in the crank case.

Another object of the invention is to provide an oil purifying and gas separating system by which the gasoline escaping past the piston rings will be returned to the carburetor or the intake manifold of the engine, and a material economy of fuel will be effected.

A further object of the invention is to pass, not only gasoline, but other volatile vapors from the crank case into the carburetor or manifold, thereby materially aiding in the lubrication of the pistons and valve stems. Such vapors are ordinarily lost through the breather tube, but with the device of the present invention, the breather tube may be sealed to retain all such vapors, and incidentally will maintain the engine much cleaner due to the fact that the escaping vapors from the breather tube will not condense on the engine head.

Further objects of the invention are to provide an oil purifying and gas separating apparatus of the general character noted above, which may be conveniently attached to any standard make of internal combustion engine, which will be of simple, practical construction, which will be rugged, durable and efficient in use, which may be readily disassembled for purposes of cleaning or repair, which eliminates the use of all complicated valve mechanism, float mechanism, and other moving mechanical parts likely to become inoperative and clog the system, and an apparatus which may be installed with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view in front elevation of an internal combustion engine with oil purifying and gas separating apparatus of the present invention associated therewith, the front end of the crank case being broken away to expose the vent at the rear end thereof.

Fig. 2 is an enlarged vertical sectional detail through the oil distilling and filtering chambers and their associated parts.

Fig. 3 is a transverse sectional detail on the line 3—3 of Fig. 2.

In the drawings I have indicated somewhat diagrammatically, an internal combustion engine 10. The crank case of the engine is represented at 11, the intake manifold at 12, the exhaust manifold at 13, oil filling pipe at 14, and the carburetor at 15. The particular location or arrangement of the conventional parts of the engine listed above is of course subject to a wide range of variation. I, having elected to show the device of the present invention as applied to one standard type of engine.

Secured upon the exhaust manifold 13 by the use of brackets 16 or other appropriate securing devices is an oil distilling and gas separating chamber 17 herein illustrated as of elongated cylindrical shape, although the particular shape of the chamber may be considerably varied. It is desirable that the chamber be of a relatively large capacity; that is to say, capable of accommodating about a pint or more of oil. Suspended below the chamber 17 in a sling 18 is a cup 19 which serves as an oil filtering chamber. A pipe 20 connected to the oil pump line enters the upper end of the chamber 17 and delivers oil under pump pressure to a pipe 21 which terminates adjacent the bottom of the cup 19 beneath a screen 22 therein. Screen 22 may be conveniently rigid or integral with an upstanding sleeve 23 encircling the pipe 21. At the top of the cup 19 there is a second screen 24 clamped between the upper end of the cup, and a seat 25 in the bottom of the chamber 17. The space between the two screens 22 and 24 is filled with a packing of filter material 26. The cup 19 is retained in proper position by a clamping screw 27 working through the bottom of the sling, and when the cup is removed, sleeve 23 facilitates the manual bodily removal of the filter material, and the ready replacement of new filtering material.

The top of the chamber 17 communicates with a pipe 28 which as shown, extends across the top of the engine and enters the intake manifold 12. This pipe near its connection with the chamber 17 is provided with a suitable regulating valve 29. The pipe 28 is a recirculation pipe for gasoline distilled in the chamber 17, or crank case vapors passing through the chamber 17 from the crank case, 10 as will be later described.

Connected at one end of the chamber 17 is an inclined pipe 30 which serves as a gravity return pipe for filtered crank case oil. This return pipe may enter the crank case at any 15 suitable point, but for the sake of convenience I have shown it as entering the oil filling pipe 14. The pipe 30 is of relatively large cross section, so that there may be a continuous gravitational downflow of oil from the distilling chamber 17, and a continuous upflow 20 above the oil of crank case vapors, such vapors being carried along by a cooling breeze through the crank case from the vent opening 31 in the rear end thereof, or at a point well 25 removed from the pipe 30.

Low manifold pressures are transmitted through the pipe 28 to the upper portion of the distilling chamber 17 and serve to maintain a continuous breeze or draft through 30 the crank case and up the pipe 30.

The operation of the device is substantially as follows. Oil under pressure from the oil circulating pipe to the engine is delivered through the pipes 20 and 21 into the bottom 35 of the cup 19, from whence it is forced upwardly through the filtering material 26 into the distilling chamber 17. Chamber 17 is maintained relatively hot due to the fact that it is arranged closely adjacent the hot exhaust 40 manifold 13. Any gasoline which may have been carried along with the crank case oil will be distilled off in the chamber 17, and will pass through the pipe 28 to the intake manifold. The oil which reaches the distilling 45 chamber 17 will be free from foreign particles, such for instance as carbon, these particles being removed by the filter material. The filtered oil will gravitationally flow down the pipe 30 through the oil intake 50 pipe 14 and back to the crank case.

Preferably the oil intake pipe is sealed by a cap 14^a, instead of providing the usual breather opening. The breather opening being in the present instance arranged at a 55 point remote from the connection of the pipe 30 with the crank case, will cause a draft of air to pass from end to end of the crank case, this draft collecting crank case vapors and carrying them along up the pipe 30 60 through the distilling chamber 17 and through the pipe 28 to the manifold.

It is frequently desirable that the manifold suction be utilized for operating a windshield cleaner or for some similar pur-

pose. In order that the pressure may not be 65 too greatly weakened by the use of the suction to maintain the circulation through the crank case and up the pipe 30, the pipe 28 is provided with the regulating valve 29. By adjusting this valve the force of the air 70 draft through the crank case and up the pipe 30 may be accurately regulated.

As noted above, the wadding or filter material at 26 may be conveniently replaced by the simple expedient of removing the cup 75 19, and the upper screen 24.

Due to the draft of air through the crank case, most of the gasoline which passes the piston rings, will not become mixed with the oil in the crank case, but while in a vaporous 80 condition will be swept along with the air current and returned to the intake manifold. The crank case vapors which are ordinarily lost through the breather tube will in the present instance be carried into the intake 85 manifold, and aid materially in the lubrication of pistons and valve stems. Due to the fact that practically all of the gasoline which escapes past the pistons is trapped 90 and reused, and due to the further fact that additional highly volatile portions of the crank case oil will be distilled and passed to the intake manifold, the apparatus of the present invention considerably adds to the mileage obtainable on a given amount of 95 fuel.

In order to observe the rate of flow of oil from the distilling chamber back to the crank case, the cap 14^a of the oil filling pipe 14 may be removed, and a visible indication 100 of the rate of flow will be afforded. All of the oil in the system will be kept sufficiently hot to act efficiently as a lubricator, and when the engine is started, the process of heating the oil to effect proper lubrication will be 105 greatly expedited.

Obviously various changes and alterations might be made in the general form and arrangement of part described without departing from the invention. Hence I do not 110 wish to limit myself to the details set forth, but shall consider myself at liberty to make such changes and alterations as fairly fall within the spirit and scope of the appended claims.

I claim:

1. The combination with an internal combustion engine including a crank case, oil pump and exhaust manifold, of filter means mounted adjacent the manifold including a 120 chamber from which filtered oil flows by gravity to the crank case, and a detachable well into which unfiltered oil is pumped, said well containing filtering material through which the oil is forced into the 125 chamber.

2. A device of the class set forth in claim 1, and wherein a sling depending from the

chamber adjustably supports the detachable well in operative relationship to the chamber.

3. In an oil purifier for internal combustion engines having an air intake, a chamber, a pipe leading to said air intake from said chamber for drawing vapors therefrom, a pipe communicating with the crank

case for delivering vapors to said first named pipe, means for introducing oil from the crank case into the chamber, and means connecting said chamber with said second named pipe for passing filtered oil through said pipe in the opposite direction to the movement of the vapors from the crank case.

JOHN G. REA.
